UNITED STATES PATENT OFFICE.

CHARLES C. GILLESPIE, OF CHICAGO, ILLINOIS.

CHEMICAL FIRE-PAIL.

No. 812,646.

Specification of Letters Patent.

Patented Feb. 13, 1906.

Application filed May 23, 1904. Serial No. 209,424.

To all whom it may concern:

Be it known that I, CHARLES C. GILLESPIE, a citizen of the United States, residing at Chicago, in the county of Cook and State of Illinois, have invented a new and useful Improvement for Chemical Fire-Pails, of which the following is a specification.

This invention relates to improvements in fire-extinguishers, and more particularly to a portable chemical fire pail or vessel.

One of the objects of the invention is the provision of means for supporting chemicals upon a receptacle; the chemicals are capable of being deposited in the receptacle when the same is in use.

Another object of the invention is the construction of a receptacle whereby the same may support a chemical-containing receptacle.

20 A further object of the invention is the provision of means for carrying a receptacle upon a fire-pail or any similar vessel, whereby the contents of the receptacle will be deposited in the pail when the handle is lifted from its normal position.

With these and other objects in view the invention consists of certain other novel constructions, combinations, and arrangements of parts, as will be hereinafter fully described, 30 illustrated in the accompanying drawings, and more particularly pointed out in the claims hereto appended.

In the drawings, Figure 1 is a view in side elevation of a device constructed in accordance with the present invention, showing the parts in their normal position. Fig. 2 is a top plan view of the device depicted in Fig. 1. Fig. 3 is a fragmentary sectional view of the primary receptacle and a fragmentary side 40 view of the auxiliary or chemical-containing receptacle. Fig. 4 is a view similar to Fig. 1, except the handle is in a raised position and the bottom of the auxiliary receptacle is open.

Referring to the drawings, F designates 45 the primary or liquid-containing receptacle constituting the fire-pail. The primary receptacle or pail F is provided with ears J. Pivotally mounted upon ears J is a handle or bail D, which is provided with a weight E, 50 constituting a grip. The weight E will normally retain the handle D in a horizontal position, Figs. 1 and 2. The portions of the handle D extending through the ears J terminate in substantially parallel rearwardly-extending portions d. The portions d of the

handle extends near to the side of the primary receptacle or pail F.

The auxiliary or chemical-containing receptacle A is supported upon the primary receptacle or pail F through the medium of substantially parallel vertical members B, secured by any suitable means to the side of the receptacle or pail F. The vertical members B are provided upon their inner face with parallel extensions H, producing grooves 60 or guideways H' upon the vertical members B. The auxiliary receptacle A is provided with sides and ends. A hinged lid a is positioned upon the sides and ends. A movable bottom C is hinged to one of the sides by 70 means of strap-hinge I. The strap-hinge I is preferably secured to the side of the auxiliary receptacle A which is nearest to the center of the primary receptacle or pail F, so that the hinged bottom C may swing toward the center of the receptacle F when the same is moved to its open position, Fig. 4. The auxiliary receptacle is provided at each end with a horizontal tongue or extension G. The tongues or extensions G are positioned within the grooves 75 H' when the auxiliary receptacle is secured upon the primary receptacle.

The handle D may be swung to a horizontal position upon opposite sides of the ears J; but it is preferable to move the handle to the 80 position shown in Figs. 1 and 2 for the purpose of placing the parallel extensions d d beneath the hinged floor or bottom for holding said bottom in a closed position, Fig. 1. When the weighted handle is in the position shown 85 in Figs. 1 and 2, its rearward extensions d d will retain the bottom snugly against the sides of the ends of the auxiliary receptacle, and thereby prevent any powdered chemicals from being deposited in the primary receptacle or pail F until the handle is lifted, 90 Fig. 4. As soon as the handle is lifted to a vertical position the bottom or floor C will swing downwardly and permit the powdered chemicals, which may be deposited in the auxiliary receptacle, to be discharged into the primary receptacle F, and consequently if any liquid—as, for instance, water—is in the receptacle F said chemicals will be dissolved in said liquid, and the same may be at 95 once used for extinguishing fire, if it is desired.

It will be noted that the auxiliary receptacle can be moved longitudinally for sliding it into its normal position upon the vertical ex- 100

tensions formed upon the primary receptacle or pail F. The vertical extensions or supports B, the tongues G, and the ends of the auxiliary receptacle A are segmental or 5 curved for conforming to the shape of that portion of the primary receptacle or pail F, upon which they are supported. The auxiliary receptacle is moved to its normal position upon the primary receptacle from near 10 the center of said primary receptacle to the rear or outer ends of the vertical extensions B, for the reason that owing to the segmental or curved structure of said members B said auxiliary receptacle could not be positioned 15 between the same from the outer side of the primary receptacle, but must be positioned between said members B by sliding the tongues G within the grooves H by an outward movement with respect to the center of 20 the primary receptacle F.

What I claim is—

1. A device of the character described, comprising a primary receptacle provided with grooved means, an auxiliary receptacle 25 provided with tenons engaging the grooved means of said primary receptacle, a weighted handle carried by said primary receptacle and provided with a rearward extension, said auxiliary receptacle provided with a hinged bottom, the extension of said handle adapted to 30 engage said bottom and hold the same in a closed position.

2. A device of the character described, comprising a primary receptacle, a weighted 35 handle provided with a rearward extension pivotally mounted upon said receptacle, a removable, auxiliary receptacle provided with a hinged bottom, carried by said primary receptacle, the rearward extension of said handle adapted to engage the horizontal bottom of 40 said auxiliary receptacle for normally retaining the same in a closed position.

3. A device of the character described, comprising a primary receptacle, vertical, 45 segmental members carried by said primary receptacle, each of said segmental members provided with a groove, a handle pivotally mounted upon said primary receptacle, a weight, constituting a grip, carried by said 50 handle, said handle provided with a rearward extension, an auxiliary receptacle provided with a hinged top and bottom, tongues carried by the ends of said auxiliary receptacle, the

tongues adapted to be positioned within the grooves of said segmental members for securing said auxiliary receptacle upon the primary receptacle, and the rearward extension of said handle adapted to normally hold the hinged bottom of said auxiliary receptacle in a closed position.

4. A device of the character described, comprising a primary receptacle, an auxiliary receptacle carried by said primary receptacle, said auxiliary receptacle provided with a hinged portion, and a handle carried by said primary receptacle adapted to engage said hinged portion for normally securing it in a closed position, said handle comprising a main body provided with integral, substantially parallel extensions, and a weight constituting a grip carried by said body.

5. A device of the character described, comprising a primary receptacle, a handle secured to said receptacle and by which the same is adapted to be handled, said handle provided with a rearward extension, an auxiliary receptacle supported upon said primary receptacle, and a hinged member carried by said auxiliary receptacle, the rearward extension of said handle adapted to normally hold said hinged member in a fixed position.

6. A device of the character described, comprising a primary receptacle, a handle secured to opposite sides of said receptacle, said handle provided with an extension, an auxiliary receptacle provided with a movable bottom carried by said auxiliary receptacle, said bottom adapted to be normally retained in its closed position by means of said extension of the handle.

7. A device of the character described, comprising a primary receptacle, a bail-handle provided with an extension carried by said primary receptacle, an auxiliary receptacle carried by said primary receptacle, and a movable closing member carried by said auxiliary receptacle, the extension of said handle adapted to engage said movable, closing member and normally hold the same in a closed position.

In testimony whereof I affix my signature in the presence of two witnesses.

CHARLES C. GILLESPIE.
